Primary Examiner — Darlington Ly

(57) **CLAIM**

The ornamental design for an automobile, as shown and described.

DESCRIPTION

The patent or application file contains at least one drawing executed in color. Copies of this patent or patent application publication with color drawing(s) will be provided by the Office upon request and payment of the necessary fee.

1. Automobile

1.1 is a front elevation view of an automobile embodying our new design;

1.2 is a rear elevation view thereof;

1.3 is a right side elevation view thereof;

1.4 is a left side elevation view thereof;

1.5 is a top plan view thereof;

1.6 is a front and left side perspective view thereof; and

1.7 is a rear and left side perspective view thereof.

Figures 1.1 to 1.7 are views of an automobile.
